UNITED STATES PATENT OFFICE.

JULIAN A. WILHELM, OF KANKAKEE, ILLINOIS, ASSIGNOR TO CHICAGO FUSE MANUFACTURING COMPANY, OF CHICAGO, ILLINOIS, A CORPORATION OF ILLINOIS.

FUSE AND JUNCTION BLOCK.

Application filed July 22, 1921. Serial No. 486,744.

The invention relates to a combined fuse and junction block for use in connection with the electric wiring in an automobile.

One of the objects of the invention is to provide a compact unitary junction block constructed with permanently secure fastening means for the terminals of the wires connected thereto, and which may be installed in a standard automobile without material rearrangement of the wires.

Another object is to provide a junction block having removable fuses for the protection of the head and tail light circuits.

A further object is to provide a junction block having connections for the selective introduction of resistance in the head light circuits, thus effecting a dimming of those lights without the use of a double filament bulb or of two bulbs.

The various terminals of the operating circuits in an automobile are usually assembled and joined in their proper relation at an accessible location on the front of the dashboard within the hood. Frequently the connections are made by means of binding posts or screws more or less insecurely fastened in the dashboard.

In some of the cheaper cars the wiring to the head and tail lights is strung along the metal frame members of the car, and by reason of the vibration attending the operation of the car the insulation is frequently worn permitting short circuits to occur which burn out the lights and cause other damage.

It is not customary in such cars to protect the lighting circuits by fuses. The invention disclosed herein is designed to supply a permanently effective means

securely joining the proper circuits and of introducing protective fuses in the lighting circuits, such means being readily installed in place of the junction blocks or other means of connection ordinarily installed by the manufacturers.

The device illustrated herein has been particularly adapted to a Ford car, and has been provided also with connections for employing resistance to accomplish the dimming of the head lights in place of the use of two circuits each to the head lights and the employment in the latter of a double filament bulb or two bulbs.

Figure 1 of the drawings represents a plan view of the fuse and junction block, with the terminals of which are diagrammatically indicated the circuits to be connected

thereto. The circuits indicated are well known to those familiar with the art and it is deemed not necessary for a proper disclosure to illustrate the complete circuits otherwise than to indicate them by the legends shown on the drawing. Fig. 2 is a side view of the device.

Referring to the drawings, the numeral 1 indicates a base of insulating material of enduring quality adapted to be secured by means of the screws 2 to the dashboard within the hood of a Ford car after the junction terminal devices previously employed have been removed. The base 1 carries four binding posts 3, 4, 5 and 6 each of which comprises a screw bolt having its slotted head 7 countersunk in the under side of the base 1 and extending upwardly therethrough, and carrying a pair of washers 8 and a pair of nuts 9 alternately arranged above the base. The binding posts effect the secure holding of the attached wires by means of the locking action between the pairs of nuts and washers.

The post 6 is in electrical contact with a bar 10 extending laterally therefrom across the surface of the base and connecting the post with a pair of suitable fuse mountings 11 and 12 which removably support one end each of a pair of removable cartridge fuses 13 and 14 having their other ends similarly secured in the fuse mountings 15 and 16 which are connected with the binding screws 17 and 18. A third cartridge fuse 19 is similarly carried by the terminal mountings 20 and 21 connected with the binding screws 22 and 23.

As indicated in Fig. 1, the fuses 13 and 14 are connected in circuit with the right and left headlights, respectively, the binding post 6 and bar 10 being connected to the bright light terminal on the instrument board switch. To effect the dimming of the lights when desired, I may install a resistance coil indicated at 24 having its terminals connected between the binding posts 4 and 6, the post 4 being connected with the dimmed head light terminal in the instrument board switch.

It will now be observed that the alternative positioning of the headlight switch to bright and dim positions will selectively throw into and out of circuit the resistance coil 24, thereby permitting the headlights to burn with full brightness or with the cur-

rent reduced by the dimmer resistance. When the ordinary installation includes two circuits from the junction block to the head lights for the control either of a two filament bulb or a pair of bulbs in each lamp, I may disconnect one of the two wires running to each of the head lights from the junction block, join them together as at 25 and effect a ground connection with the frame of the car as indicated in dotted lines at 26. The fuse 19 is connected as indicated in circuit with the tail light, the binding screw 22 being connected with the tail light terminal in the lighting switch on the instrument board.

It will now be apparent that the fuses introduced into the head and tail light circuits between the source of current and the lights will serve to protect the latter against any excessive current occasioned by extreme speed of the generator or by short circuiting of those circuits.

It will also be apparent that my device may be readily installed by simply displacing the former junction block and making the connections as theretofore with the binding posts in my improved device.

I claim as my invention:

1. A combined unitary junction and fuse block adapted to be inserted in lighting systems without alteration of the existing wiring, including a live switch terminal, a bright headlight terminal, a dimmer headlight terminal, either of said last two mentioned terminals being arranged selectively to be connected with said live terminal, a conductor bar connected directly with one of said terminals and having a pair of fuse terminal recesses thereon, removable right and left headlight fuses having their one end set in said recesses, and a pair of fuse

terminal connectors arranged to cooperate with the other ends of said fuses each having connection respectively with said right and left headlights.

45

2. A combined unitary junction and fuse block adapted to be inserted in lighting systems without alteration of the existing wiring, including a live switch terminal, a bright headlight terminal on one side of said live terminal, a dimmer headlight terminal on another side, either of said terminals being arranged selectively to be connected with said live terminal, a conductor bar connected to said bright headlight terminal and having a pair of fuse terminal recesses thereon, removable right and left headlight fuses set in said recesses at one end, a pair of fuse terminal connectors receiving the other ends of said fuses and having connection respectively with said right and left headlights, and a resistance constituting a connection between said bright and dimmer headlight terminals.

60

3. A unitary device of the character described, comprising a block of insulating material adapted to be mounted upon the dash board of an automobile, a plurality of terminals mounted on said block comprising a bright headlight terminal, a conducting bar having two fuse clips integral therewith connected to said bright terminal, two other fuse clips cooperating with said first mentioned fuse clips to hold headlight fuses, a dimmer headlight terminal, a terminal adapted to be connected to a source of supply, said last named terminal adapted to be connected to either of said bright or dimmer headlight terminals, respectively.

65

In testimony whereof, I have hereunto set my hand.

JULIAN A. WILHELM.
